UNITED STATES PATENT OFFICE

121,174

DESIGN FOR A HOPPER MECHANISM HOUSING FOR STOKERS

Gilbert M. Seaman, Catskill, N. Y., assignor to
Catskill Metal Works, Inc., Catskill, N. Y., a
corporation of New York

Application April 19, 1939, Serial No. 84,488

Term of patent 7 years

To all whom it may concern:

Be it known that Gilbert M. Seaman, a citizen
of the United States and resident at Catskill, in
the county of Greene and State of New York,
has invented a new, original, and ornamental
Design for a Hopper Mechanism Housing for
Stokers, of which the following is a specification,
reference being had to the accompanying drawing,
forming part thereof.

Fig. 1 is a front elevational view of a hopper
mechanism housing for stokers embodying my
new design;

Fig. 2 is a top plan view thereof; and
Fig. 3 is a side elevational view thereof.
The stippled portions of the drawing indicate
a color appearance contrasting with the remain-
ing portions of the housing.

I claim:

The ornamental design for a hopper mecha-
nism housing for stokers, as shown and described.
